UNITED STATES PATENT OFFICE.

GUY SANTOMAURO, OF LOS ANGELES, CALIFORNIA.

HAIR-CLIPPER.

1,260,247.

Specification of Letters Patent. Patented Mar. 19, 1918.

Application filed January 8, 1917. Serial No. 141,156.

To all whom it may concern:

Be it known that I, GUY SANTOMAURO, a citizen of the United States, residing at Los Angeles, in the county of Los Angeles and

5 State of California, have invented new and useful Improvements in Hair-Clippers, of which the following is a specification.

This invention relates to hair clippers, and pertains especially to that type of clip-
10 per having a cutting bar provided with teeth upon which reciprocates a knife bar provided with corresponding teeth.

Heretofore in cutting hair with clippers to produce a feather hair cut, a fine clipper
15 which cuts the fine hair close to the neck and cuts it short has been used at the base of the head. A second clipper is then used farther up on the head just above the cuts made by the fine clipper. This second clip-
20 per is coarser and produces a hair stubble of greater length than the first clipper. The use of two clippers alone produces a ridge between the stubble left by the fine clipper and the stubble left by the coarse clipper.
25 In order to effect a neat appearing job, it has been necessary for the operator to pick out the hairs on the ridge between the two different length stubbles by means of a comb and cut with scissors to produce a surface
30 at the ends of the stubble which uniformly tapers from the short stubble to the long stubble. This is a very tedious operation and requires a very expert operator to effect a neat job. The work consumes a rela-
35 tively great length of time even with the most expert operator and the effect produced is not perfect.

It is an object of this invention to provide a clipper which may be used to cut hair so as to leave a stubble graduated from a short to a longer stubble.

It is another object of this invention to provide a clipper which will do the work of both the fine and coarse clippers, and
45 which will do work intermediate of the two clippers before mentioned.

My improved clipper is intended to do away with the coarse and fine clippers above referred to, and comprises a clipper, which
50 in general appearance, is the same as the ordinary hair clipper, but has a heel on its lower surface.

I accomplish these objects by means of the embodiment of my invention illustrated
55 in the accompanying drawing, in which:

Figure 1 is a side view of a clipper.

Fig. 2 is a fragmentary view of the bot-
tom of a modified form.

Fig. 3 is a front view of a modified form
of clipper.

More specifically, 4 indicates a cutter bar which is comprised of a body of substan-
tially rectangular form, and is provided at the front edge with a series of cutting teeth
5. Secured to the body of the cutter bar 4
65 is a handle 6. Handle 6 is preferably inte-
gral with the cutter bar, but may be con-
nected in any manner found expedient. The
handle 6 is provided with a finger thumb
70 grip 7, and is of the form usual in clippers.
The knife bar is indicated by 8, and is
provided with teeth which correspond to
the teeth on the cutter bar. The knife bar
8 is mounted upon cutter bar 4 in such pos-
75

ition that it may be reciprocated with re-
spect to the cutter bar, and is provided with
the usual means for guiding it in its move-
ment. A handle 9 for reciprocating the cut-
ter bar is mounted within the body 12 of
the clipper, and is suitably connected to the
80 knife bar. The handle 9 is provided with a
finger stop 10 of the usual form. The con-
struction just described is that of an ordi-
nary clipper.

My clipper differs from the ordinary
85 clipper in that, the surface of the cutter
bar is provided with a raised heel portion
indicated by 13 in Fig. 1. The heel shown
in Fig. 1 is preferably integral with the
cutter bar. The heel portion may be detach-
90 able and adjustable, as shown in Figs. 2
and 3. In Figs. 2 and 3, a heel bar 14 is
disposed upon the surface of the cutter bar.
Side fingers 15 and 16 are provided which
grip the upper surface of the cutter bar, and
95 hold the heel bar upon the cutter bar in
any adjusted transverse position.

In the use of my improved clipper, the
heel rests against the head and the clipper
may be rocked about the heel. When it is
100 rocked forward with the teeth close to the
head a fine cut is made in the hair. As the
hair is cut upward upon the head the clip-
per is rocked about the heel with the teeth
away from the surface of the head, thereby
105 cutting a longer stubble. In this way hair
may be graduated and a single clipper used.
The handles of the clippers 6 and 9 are
shortened in order that the clipper may be
properly rocked and to allow room for
110 working in and around the coat collar and
the neck when cutting hair.

What I claim is:

In a device of the class described, the combination of a hair cutting mechanism provided with a grooved cutter bar having cutting teeth at its front edge, a knife bar reciprocally mounted on the cutter bar, of a heel plate having a flat inner face and a grooved outer surface, the grooves in said surface registering with the grooves formed in the cutter bar, the transverse thickness of said heel plate varying from its two longitudinally disposed knife edges to the cen-

ter thereof, said surface being of a curved configuration, and a grooved upstanding flange on each of the transverse sides of said heel plate adapted to frictionally and adjustably engage the cutter bar of said cutting mechanism, whereby the heel plate may be disposed in any desired position on the cutter bar.

In witness that I claim the foregoing I have hereunto subscribed my name this 21st day of December, 1916.

GUY SANTOMAURO.
